CONSECUTIVE STATIONS COMMUNICATION SYSTEM

Charles Oliver Tucker and Otto H. Gotsch,
Watsonville, Calif.

Application February 28, 1945, Serial No. 580,176

4 Claims. (Cl. 179—1)

1

The present invention relates to improvements in a consecutive stations communication system, and it consists of the combinations, constructions and arrangements hereinafter described and claimed.

In the various hospitals where a great number of patients are cared for, it is almost impossible to keep in constant touch with all of them throughout the day and night. Should a patient's condition become critical and he be unable to communicate this fact to an attendant, serious consequences might result.

The principal object of our invention is to provide a consecutive stations communication system in which each patient is placed in communication with a central agency such as a call station periodically throughout the day and night and each time this communication is established, the condition of the patient can be checked by the nurse or other attendant on duty. The checking can be accomplished by the attendant listening to any peculiar noises or breathing being emitted by the patient. In case the patient is unconscious or in pain the particular noise will be conveyed to the call station.

Novel means is provided for successively bringing all of the patients into communication with the call station and when the circuit is established between any particular bed in a ward and the call station, both the patient and the attendant may communicate with each other. If desired a signal system may be arranged for indicating when any particular bed is in communication with the call station so that the patient occupying the bed will know when he may talk and be heard at the station.

The device is not limited to hospitals since a large company having various departments can have this device installed and the departments successively placed in communication with a central station so that orders may be transmitted between the particular department and the central headquarters. The device can be used as an listening device for checking in on various departments throughout the day if desired.

The device is simple to install and is inexpensive to operate.

Other objects and advantages will appear in the following specification, and the novel features of the device will be particularly pointed out in the appended claims.

Our invention is illustrated in the accompanying drawing forming a part of this application, in which:

The figure is a schematic showing of the operating mechanism and sets forth the necessary wiring for carrying out the invention.

While we have shown only the preferred form

2

of our invention, it should be understood that various changes or modifications may be made within the scope of the appended claims without departing from the spirit and scope of the invention.

In carrying out our invention we provide an electric motor or other power service indicated generally at A and this motor is operatively connected to a gear reduction box, indicated schematically at B. A shaft 14 extends from the box B and the shaft will be rotated at any desired speed by adjusting a control knob 12 that has a pointer 13 swingable from "slow" position indicated by "S" to a "high" position indicated by "F." The letters "S" and "F" are indicated at 14 and 15 respectively.

The shaft 14 is connected to a shaft 16 by a coupling 17 made of insulation. The insulation prevents any electrical current from passing from one shaft to the other. The shaft 16 extends through the center of a dial C. The dial has a series of consecutive numbers 1 to 6 inclusive and these are arranged around the periphery of the dial and designate terminals which are given reference numerals 1 to 6 inclusive. A wiper switch arm 18 is carried by the shaft 16 and has a terminal 19 that is adapted to successively contact the terminals 1 to 6 inclusive as the shaft 16 is rotated in a clockwise direction by the shaft 14.

Another shaft 20 is connected to the shaft 16 and is electrically insulated therefrom by the insulating coupling 21. The shaft 20 extends through the center of a second dial D and this dial has numbers 1 to 6 arranged around its periphery and placed in the same relative positions as the numbers 1 to 6 are placed on the dial C. The dial D has its terminals given reference numerals 1a to 6a inclusive. These terminals are associated with the numbers 1 to 6 on the dial D. The shaft 20 carries a wiper switch arm 22 which is similar to the arm 18 and the arm 22 has a contact member 23 that successively contacts the terminals 1a to 6a inclusive as the arm revolves.

In the present form of the invention we have illustrated a hospital ward having six beds numbered 1 to 6 inclusive and we have shown a call station board diagrammatically at E. The board has a plurality of lights thereon numbered 1 to 6 inclusive; light numbered 1 being associated with bed number 1, light numbered 2 being associated with bed numbered 2, etc. A loud speaker and amplifier is indicated generally at F and is mounted on the board E. Each bed is equipped with a microphone and these are given reference numerals 1b to 6b inclusive. The microphones are successively and electrically connected to the loud-speaker F for short periods of time and this will permit the patients in the

bed to communicate with the attendant at the call station when their turn comes. It is obvious that the microphones and the loud-speaker can include a two-way speaking device which will permit the patient to converse with the attendant at the call station and vice versa.

From the foregoing description of the various parts of the device, the operation thereof may be readily understood.

When the electric motor causes the sweep hands 18 and 22 to contact with the terminals 2 and 2a on the dials C and D, an electric circuit will be closed to illuminate the light 25, numbered 2, and a second circuit will be closed from the microphone 2b of the bed 2 to the loud-speaker F.

In the first circuit, a current will flow from the battery G through wire 31 to the sweep hand 22. The current will then pass through the contacts 23 and 2a and flow along the wire 30. The wire 30 has a wire 26 connected thereto that leads to the light 25 on the call station board E, this light being numbered 2. The current then flows from the light 25 through wires 24 and 33 to ground 34. The battery G is connected by wire 27 to ground 32 and this completes the electrical circuit. The operator at the call station E will know that when the light 25 (numbered 2) is illuminated, the microphone 2b for the bed or station 2 will be in electrical communication with the loud speaker F.

Should the patient in bed 2 desire to be made aware when his microphone 2b is in communication with the loud speaker F, he can close a switch 29 placed near his bed, and this switch is connected to the wire 30 and to a signal light 28 positioned near the bed. When a current flows through the wire 30 and on through the wire 26, the closing of the switch 29 will place the light 28 in parallel with the light 25 because the light 28 is connected to ground 28'. When therefore the switch 29 is closed, both lights 25 and 28 will be illuminated when the sweep arm 22 brings contact 23 into electrical contact with the terminal 2a.

In connection with the microphone circuit, it will be noted that the loud speaker F is connected to ground 35 by wire 36. The loud speaker and amplifier has the necessary source of electrical current and the usual radio equipment to cause the loud speaker to operate in the customary manner. A wire 37 leads from the loud speaker F to the sweep arm 18 and since the terminal 19 of the arm is electrically connected to the terminal 2 on the dial C, current will flow through the wire 38 to the bed microphone 2b. A wire 39 leads from the bed microphone to ground 40 thus completing the circuit. It is possible for the patient to talk to the attendant at the call station so long as the terminal 19 contacts with the terminal 2 and if desired the microphone 2b can be a two-way radio speaking device with the loud speaker F also being a two-way speaking device.

The patient can turn off the switch 29 at his bed at any time desired and this will cut out the current flowing to the light 28, yet the light 25 on the call station board E will be illuminated each time the bed microphone 2b is electrically connected to the loud speaker F. Should the patient be too sick to talk, any sounds emitted by him will be picked up by the microphone and transmitted to the loud speaker. This will warn the attendant at the call station if the patient is in a critical condition.

The gear reduction box B can have its mechanism controlled by the knob 12 so that the shaft 11 will rotate at the desired speed and thus change the time interval at which the microphone 2b will be electrically connected with the loud speaker F. All of the other beds or stations will have their microphones electrically connected with the loud speaker F in their proper turn. The drawing illustrates the wiring necessary to accomplish this but no further description of the other circuits need be given since they will function in the same manner as the circuits described in connection with bed or station number 2.

The motor is designed to operate continuously and the lights 25, numbered 1 to 6 inclusive on the call board E, will be successively illuminated. Each time a light on the board is illuminated the attendant knows that the particular bed or station corresponding with the number on the light has its microphone in electrical connection with the loud speaker F. It is discretionary upon the part of the patient whether or not he wishes his signal light 28 to indicate periodically when his microphone is placed in electrical connection with the loud speaker F. As already stated, the device can be used for other purposes than keeping in contact with patients in a hospital.

We claim:

1. A device of the type described comprising a plurality of stations, a microphone for each station, a central station having a loud-speaker, means for successively and continuously bringing all of the stations into electrical connection with the loud-speaker so that two-way communication can be established between each station and the central station so long as said means electrically connects the station with the loud-speaker, and means including lights and controlled by said first-named means for indicating at the central station the particular one of the first-mentioned stations that has its microphone in electrical connection with the loud-speaker.

2. A device of the type described comprising a plurality of stations, a microphone for each station, a central station having a loud-speaker, means for successively and continuously bringing all of the stations into electrical connection with the loud-speaker so that two-way communication can be established between each station and the central station so long as said means electrically connects the station with the loud-speaker, and means including lights and controlled by said first-named means for indicating at the central station the particular one of the first-mentioned stations that has its microphone in electrical connection with the loud-speaker, said last-named means including additional lights associated with the stations and adapted to be lighted in synchrony with the proper one of said first-named lights, whereby a person at the station will know when the station microphone is connected to the loud-speaker.

3. In combination, an electric motor, a dial having a number of contacts thereon, a switch arm movable over the contacts, means operatively connecting the arm to the motor for causing the latter to swing the former at the desired speed, a plurality of stations equal in number to the number of contacts, a microphone for each station and electrically connected to the proper contact, a central station having a loud-speaker successively and electrically connected to the microphones in the various stations by the arm moving over the contacts, lights at the central station corresponding in number to the number

of stations, each light designating a particular station, and means actuated by said first-named means for connecting the lights with a source of current, said last-named means causing the proper light to be illuminated that designates the particular station microphone is electrically connected to the loud-speaker.

4. In combination, an electric motor, a dial having a number of contacts thereon, a switch arm movable over the contacts, means operatively connecting the arm to the motor for causing the latter to swing the former at the desired speed, a plurality of stations equal in number to the number of contacts, a microphone for each station and electrically connected to the proper contact, a central station having a loud-speaker successively and electrically connected to the microphones in the various stations by the arm moving over the contacts, lights at the central station corresponding in number to the number of stations, each light designating a particular station, and means actuated by said first-named means for connecting

the lights with a source of current, said last-named means causing the proper light to be illuminated that designates the particular station microphone is electrically connected to the loud-speaker, station lights, and means for connecting the station lights into the circuits that cause said first-named lights to illuminate, whereby the station lights will designate when the station microphone is electrically connected to the loud-speaker.
